Helen L. Basore, Pasadena, Calif., assignor to
Preston-Poynter Foundation, Pasadena, Calif.,
a corporation of California

Application June 26, 1953, Serial No. 25,681

Term of patent 7 years

(Cl. D44—21)

To all whom it may concern:

Be it known that I, Helen L. Basore, a citizen of the United States, residing at Pasadena, in the county of Los Angeles and State of California, have invented a new, original, and ornamental Design for a Pitcher, of which the following is a specification, reference being had to the accompanying drawing, forming part thereof, and wherein:

Fig. 1 is a right side elevational view of a pitcher, showing my new design;

Fig. 2 is a front elevational view thereof;

Fig. 3 is a left side elevational view thereof; and

Fig. 4 is a top plan view thereof.

I claim:

The ornamental design for a pitcher, substantially as shown.

HELEN L. BASORE.
